FOREIGN PATENT DOCUMENTS

- WO WO 2010/151848 12/2010

Primary Examiner — Steven J Czyz*(74) Attorney, Agent, or Firm* — Gerard M. Donovan; Amardeep S. Grewal; Reed Smith LLP(57) **CLAIM**

The ornamental design for a hydration system valve, as shown and described.

DESCRIPTION

FIG. 1 is a top perspective view of a hydration system valve showing the design.

FIG. 2 is a top plan view of the design.

FIG. 3 is a bottom plan view of the design.

FIG. 4 is a left side elevation view of the design.

FIG. 5 is a right side elevation view of the design.

FIG. 6 is rear elevation view of the design; and,

FIG. 7 is a front elevation view of the design.

The broken lines depict environment that forms no part of the claimed design.

1 Claim, 7 Drawing Sheets---
